HIGH-VACUUM SEAL

William M. Hickam, Pittsburgh, Pa., assignor to
Westinghouse Electric Corporation, East Pitts-
burgh, Pa., a corporation of Pennsylvania

Application December 6, 1949, Serial No. 131,409

11 Claims. (Cl. 250—41.9)

1

This invention relates generally to a high vacuum seal, and, more particularly, to a gasket-type seal for maintaining low pressures inside an evacuated container, such as, for example, a mass spectrometer tube. The invention is described as applied to a mass spectrometer tube of metal wall construction, a metal construction being used for reasons of strength. The invention, however, is not restricted to metal since it is useful for tubes having glass walls, or for other types of vacuum electrical apparatus, such as thermionic or electron discharge apparatus in general.

Heretofore, in the operation of a mass spectrometer tube, considerable difficulty has been encountered because of the necessity for heating the tube, either for the purpose of degasifying it preparatory to introduction of a new sample in the ion source, or for preventing the occurrence of cold spots. Molecules of the sample emanating from the ion source tend to accumulate on these cold spots and, therefore, prevent attainment of a constant flow rate of a gaseous sample and accurate analysis. Molecules remain on the cold spots after removal of the sample, evacuation of the tube and introduction of a new sample thus giving rise to background peaks which interfere with the analysis of the new sample and which can only be easily eliminated except by a prolonged bake-out of the tube.

The necessary heating of the walls gives rise to difficulties with respect to the sealing material which usually comprises wax, rubber, or other low melting point plastic materials. Heating, of course, tends to melt the wax or rubber and cause breakdown of the seal. Wax seals are desirable because of the ease of melting and solidification thereof which readily permits periodic removal of the electrodes for cleaning. Such cleaning is necessary since the reaction which occurs in the presence of the filament forming part of the ion source causes an insulating film to form on the electrodes which affects the electrical field so as to make erratic performance of the mass spectrometer tube. In the use of glass tubes without a wax or similar seal, removal of the electrodes may be accomplished solely by cracking the walls which can be done only by an experienced glass blower.

In the past, in view of the high vacuum required in certain types of electronic tubes, it has been attempted to insure maintenance of such high vacuum by completely surrounding the evacuated tube by a second tube and evacuating the space between the respective walls thereof. Such construction, however, has been found un-

2

desirable not only because of the substantial expense involved in providing an additional tube, but because of the difficulty in providing electrode leads and pumping leads through the walls of both tubes—also because of the difficulty in maintaining the respective seals.

An object of the present invention is to provide a high vacuum seal which is devoid of the above-mentioned disadvantages of common types of seals.

A more specific object of this invention is to provide a high vacuum seal which is particularly suitable for maintaining a high vacuum in an evacuated container, such as, for example, a mass spectrometer tube, and which permits easy access to the electrode system located in the container.

A further object of this invention is to provide a gasket type seal for a high vacuum tube, such as a mass spectrometer tube, which maintains, for long periods of time, extremely low pressures within the tube over a wide temperature range and permits the entire system to be operated at high temperatures without detrimentally affecting the seal.

In accordance with these objects I provide a vacuum chamber having two sections. The line of the junction only is surrounded by an intermediate pressure chamber formed between the inner chamber and a projection on the flanges of the two parts of the vacuum chamber.

The novel features that I consider characteristic of my invention are set forth with particularity in the appended claims. The invention itself, however, both as to its organization and its method of operation together with additional objects and advantages thereof will best be understood from the following description of a specific embodiment when read in connection with the accompanying drawing, in which the single figure is a longitudinal, cross-sectional view of a portion of a mass spectrometer tube adjacent the ion source and embodying a seal in accordance with the teachings of the present invention.

The apparatus shown in the drawing includes a fixed tubular section 1 and a removable tubular section 2 of a portion or extension of a mass spectrometer tube that surrounds an ion source 3. The tube is preferably made of metal such as stainless steel, Monel metal, iconel, or other suitable alloy or metal, although it should be understood that it may be made, instead, of glass, ceramic or other suitable material. The top portion of section 2 has a disk-shaped end wall 2a

brazed, welded, or otherwise permanently connected in an air-tight seal to the tubular section 2. A seal 4 is provided between the lower end portion of section 2 and a shoulder portion formed on the inner wall of section 1. This seal is made of material that will withstand heat normally applied to these sections, preferably gold in the shape of wire, since gold anneals at relatively low temperatures, that is, in the neighborhood of 200° C., and since portions thereof can be joined together very simply by heating such as by means of a torch. Other metals, such as aluminum or copper, may be used instead, but these have a higher coefficient of expansion than that of the metal sections 1 and 2, and, therefore, may not match the coefficient of these sections as well as gold will. As the gold becomes hardened, as most metal seals do from continued operation, it is an easy matter to raise the temperature sufficiently to effect softening or annealing thereof.

Integrally secured to section 2 is an annular flange 5 having extending therefrom and integrally secured thereto a skirt or cylindrical outer wall member 6 terminating at the lower end thereof with a sealing shoulder for accommodating a seal 7 preferably of rubber or other plastic material having relatively low melting temperature. The upper portion of fixed section 1 is of reduced thickness and terminates in a sealing edge which engages seal 7. An intermediate pressure chamber 12 is formed between the wall of section 1 and the wall of section 2 adjacent to the seal 7. Since the intermediate pressure region is at approximately 10^{-3} mm. high pressure, it is a poor conductor of heat. Substantially all of the heat from the interior of the high vacuum chamber reaching the seal 7 will be conducted through the thin wall portion on movable section 2 at the top of the intermediate pressure chamber 12 and through the wall portion of section 1 at the bottom of the intermediate pressure chamber 12. Since both skirt 6 and the upper portion of section 1 are substantially thinner than the portions of sections 1 and 2 forming the inner wall of the tube, they restrict conduction of heat from the inner walls of the tube to seal 7. To prevent heating of rubber seal 7, cooling coils 8 are provided on the respective outer wall portions for conducting a cooling fluid, such as water, to dissipate the heat as it is conducted along these thin sections.

The outer seal 7 need not be made of rubber. It may be made of gold or any other material, which would be suitable in the seal 4. The flanges must then be machined with greater accuracy, because a variation of greater than 0.001 inch may make one of the two metal seals defective.

To join the two sections 1 and 2 tightly and maintain pressure on the seals, there is provided a plurality of bolts, such as the bolt 9, whose lower ends are welded or otherwise secured to the metal base 5a of the section 1 of the spectrometer tube, and whose upper threaded ends extend through holes in the annular flange 5. Nuts 10 are screw threaded to the upper ends so that by tightening the nuts, sections 1 and 2 are brought tightly together so as to compress seals 4 and 7.

Cylinders or tubes, such as 11, are provided for connection to a vacuum pump (not shown) for maintaining the space within sections 1 and 2 at low vacuum pressure, usually of the order of 10^{-7} mm. Hg. The intermediate vacuum chamber 12, made vacuum-tight by seals 4 and 7, is

connected by means of a tube 13 to a low-vacuum pump of the high vacuum pump (not shown) and is preferably maintained at an intermediate pressure of the order of 10^{-3} mm. Hg. Thus, since there is a considerably smaller differential of pressure, between the interior of the tube and intermediate chamber 12 than between the interior and the surrounding atmosphere outside of the tube, there will be less tendency toward leakage through seal 4. Furthermore, since the portion of section 2 below flange 5 is surrounded by vacuum, heat will be readily conducted along the inner wall rather than across the intermediate vacuum chamber 12.

In operation, the multi-section tube is assembled as follows: Removable section 2 is placed over fixed section 1. Sufficient rubber or other plastic material is provided to form seal 6 so that it will contact both the removable and fixed sections 2 and 1 before the gold gasket or seal 4 makes contact. Therefore, the rubber gasket 7 is under some compression before the gold gasket 4 is sealed. Pressure is then applied to these two seals by tightening nuts 10. The intermediate pressure chamber is then evacuated to approximately 10^{-3} mm. Hg through tube or pipe 13 while the high pressure chamber of the mass spectrometer tube is evacuated through cylinder 11 to approximately 10^{-7} mm. Hg.

While I have illustrated and described a certain specific embodiment of my invention, it will be apparent that this is by way of illustration only, and that various changes and modifications may be made within the contemplation of my invention and within the scope of the following claims.

I claim as my invention:

1. An evacuated container comprising a pair of metal tubes, a seal comprising a gold ring for joining said tubes for forming a continuous envelope, an extension integrally formed on and extending outwardly from one of said tubes in the vicinity of said seal, a second extension integrally formed on the other of said tubes and surrounding a portion thereof in spaced relationship, a second seal comprising a plastic material for sealing the ends of said respective extensions in a gastight manner so that said extensions and a portion of said other tube form an airtight enclosure, said enclosure being evacuated to lesser degree than the space enclosed by said tubes.

2. Apparatus recited in claim 1 wherein said second seal consists of plastic material of relatively low melting point and wherein said extensions are of lesser thickness than said tubes so as to restrict conduction of heat from said tubes to said plastic seal.

3. Electrical vacuous apparatus comprising a fixed metallic tubular member having an inner shoulder adjacent one end thereof and a removable metallic tubular member whose end is fitted against said shoulder, a metallic sealing material at said shoulder for providing a gastight joint between said members, said fixed member having an outwardly extending portion in spaced relationship to and surrounding a portion of said removable member, said removable member having an integral flange and a depending skirt extending from said flange which surrounds a portion of said removable member, a second seal of plastic material for sealing the end of said skirt to the end of said outwardly extending portion, thereby providing a small airtight enclosure, said skirt and outwardly extending portion being of

thinner material than said tubular members to restrict conduction of heat from said members to said plastic seal.

4. Apparatus recited in claim 3 together with cooling coils mounted on said skirt and said outwardly extending portion adjacent said second seal of plastic material to maintain the temperature of said seal below a predetermined value and wherein said enclosure is evacuated to a lesser degree than the space defined by said tubular members.

5. A mass spectrometer tube comprising electrode means, said tube being made of metal and including a fixed tubular portion having an inner shoulder and a removable tubular portion whose end is seated on said shoulder, a seal in the form of a gold wire between said shoulder and end, said fixed tubular portion having an integral extension surrounding, in spaced relationship, the end portion of said removable tube portion, an annular flange integrally formed on and surrounding said removable portion and having a depending skirt, a rubber seal between the ends of said skirt and of said extension thereby forming an air-tight, small intermediate chamber, cooling coils mounted on said skirt and on said extension adjacent said rubber seal to maintain the temperature of said rubber seal below a predetermined value, said intermediate chamber being evacuated to a less extent than said mass spectrometer tube so as to reduce the pressure differentials across said respective seals, a plurality of bolts having one end integrally secured to said fixed tubular portion and the other end threaded and extending through holes formed on said annular flange, nuts on said threaded ends, the tightening of which simultaneously compresses both of said seals, tubular means formed on said fixed tubular portion for connection to a vacuum pump for evacuating said mass spectrometer tube, and second tubular means formed on said extension for connection to a fore pump for evacuating said intermediate chamber to a lesser extent than said mass spectrometer tube; whereby said removable portion is detachably secured to said fixed tubular portion in a vacuum-tight manner to permit access to said electrode means, and whereby the respective seal may be adjustably compressed by tightening of said nuts.

6. For use in sealing a two-piece vacuum chamber, the interior of which will be heated, the combination comprising a first seal at the inner edge of the line of junction between the two pieces of the vacuum chamber, said first seal being formed of a material having the resistance characteristics that enable it to withstand the heat to which the chamber is subjected, means forming a chamber around said first seal, said last named chamber having a second seal of a more easily compressible material, outlet connections in said last named chamber for evacuating it to a pressure between atmospheric and the pressure in the inner chamber, and connecting means for pressing said two pieces of said vacuum chamber together.

7. For use in sealing a two-piece vacuum chamber, the interior of which will be heated, the combination comprising a first seal at the inner edge of the line of junction between the two pieces of the vacuum chamber, said first seal being formed of a material having the resistance characteristics that enable it to withstand the heat to which the chamber is subjected, means forming a chamber around said first seal, said last

named chamber having a second seal of a more easily compressible material, outlet connections in said last named chamber for evacuating it to a pressure between atmospheric and the pressure in the inner chamber, and connecting means for pressing said two pieces of said vacuum together so that said second seal is contacted by said two pieces when said first seal is contacted.

8. For use in sealing a two-piece vacuum chamber, the interior of which will be heated, the combination comprising a first seal at the inner edge of the line of junction between the two pieces of the vacuum chamber, said first seal being formed of a material having the resistance characteristics that enable it to withstand the heat to which the chamber is subjected, means forming a chamber around said first seal, said last named chamber having a second seal of a more easily compressible material, outlet connections in said last named chamber for evacuating it to a pressure between atmospheric and the pressure in the inner chamber, and connecting means for pressing said two pieces of said vacuum chamber together and cooling means for cooling the chamber adjacent said second seal.

9. For use in sealing a two-piece vacuum chamber, the interior of which will be heated, the combination comprising a first seal at the inner edge of the line of junction between the two pieces of the vacuum chamber, said first seal being formed of a material having the resistance characteristics that enable it to withstand the heat to which the chamber is subjected, means forming a chamber around said first seal, said last named chamber having a second seal of a more easily compressible material, outlet connection in said last named chamber for evacuating it to a pressure between atmospheric and the pressure in the inner chamber, and connecting means for pressing said two pieces of said vacuum chamber together and tubes on either side of said second seal for cooling said seal.

10. A two-piece vacuum chamber having an inner region of low pressure, a region of higher pressure, a first washer of heat-resistant material at the junction point between the two pieces between the regions of low and higher pressure, and a second washer of a plastic material between the two sections between the region of higher pressure and the outside of said chamber.

11. A two-piece vacuum chamber having an inner region of low pressure, a region of higher pressure, a first washer of heat-resistant material at the junction point between the two pieces between the regions of low and higher pressure, a second washer of a plastic material between the two sections between the region of higher pressure and the outside of said chamber, and means for exerting pressure to hold said two sections in contact, said last named means being arranged to compress said second washer before contacting said first washer.
